UNITED STATES PATENT OFFICE.

ESSEX L. LOMAX, OF WASHINGTON, DISTRICT OF COLUMBIA, ASSIGNOR OF
ONE-HALF TO FREDERICK S. GICHNER, OF SAME PLACE.

BATTER-DROPPER.

SPECIFICATION forming part of Letters Patent No. 538,655, dated February 5, 1895.

Application filed June 8, 1894. Serial No. 513,934. (No model.)

To all whom it may concern:

Be it known that I, ESSEX L. LOMAX, a citizen of the United States, residing at Washington, in the District of Columbia, have invented certain new and useful Improvements in Batter-Droppers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to that class of liquid droppers especially applicable to batter-pots, and it is intended as an improvement upon those droppers wherein the valve mechanism is located within the batter-pot and also upon those which have complicated mechanism located on the outside. My purpose is to so construct the cut-off valve and its associated parts as to prevent the accumulation of matter in the parts, to cut off the batter so perfectly that there will be no dripping after the valve is closed, and also to connect the valve with its operating lever in such a way that it can be easily removed for cleaning purposes.

To these ends my invention consists of a cut off valve peculiarly arranged to operate across an outlet in the bottom of the batter pot, in connection with certain peculiar external mechanism for operating the valve, all of which will be more fully described herein-after and pointed out in the claims.

In the accompanying drawings: Figure 1, represents a side elevation of my complete invention, in which the valve is shown in closed position, and dotted lines represent it in open position. Fig. 2, is a bottom view thereof, and Fig. 3 a detail sectional view of the valve and its immediate parts.

The reference letter *a*, denotes a batter pot provided with a funnel shaped bottom *b*, which terminates in a short cylindrical nozzle *c*. The interior of the nozzle is reduced by means of a collar *d*, which forms a smooth widened surface for the cut-off valve *e*, to slide upon. This widened bearing creates a tighter joint between the valve and nozzle than would be the case if it were simply moved across a surface having only the thickness of the tin out

of which batter pots are usually made. The valve is held snugly against the collar and guided in its reciprocations by a pair of guide lugs *f*. These lugs overlap longitudinal raised surfaces on the valve *g*, which are adapted to receive the wear from the guide lugs, and they also serve to stiffen the valve which is made preferably of a double thickness of tin. Located near the center of the valve is a circular orifice *h*, adapted to register with the opening in the nozzle in the operation of dropping a portion of batter. The means for actuating the valve consists of a curved thumb rod *i*, the upper portion of which passes through the handle *a'*, at a point convenient for the thumb when the handle is grasped. The lower end of this rod is pinned jointed to a bell-crank lever *j*, fulcrumed in the bracket *k*, attached to the side of the pot. The lower end of the lever passes into an oblong hole *l*, through the valve or slide. This hole is larger than the end of the lever in order to allow the latter to operate loosely therein when actuated by the rod *i*. The cut-off valve is automatically returned to cut off the flow of batter, through the medium of a coil spring *m*, having its opposite extremities connected to the bell crank lever and to an eye *n*, respectively. The valve is limited in its backward thrust by an upturned lip *o*, which comes in contact with the side of the nozzle *c*.

The funnel portion of the pot is provided with legs *b'* which support the pot when not in use.

The operation of the device will be briefly described as follows: When it is desired to allow a portion of the contents to drop upon a frying pan when cooking, or when using the utensil for other purposes, the operator has only to grasp the handle and depress with the thumb the rod *i*, which in turn operates the bell crank lever against the tension of the coil spring. The lower arm of the lever is thus moved forward carrying with it the cut-off valve, bringing the opening therein into coincidence with the opening in the bottom of the nozzle and allowing the liquid to pass out. When the thumb is withdrawn from the button on the rod *i*, the spring will operate to move the parts back to their for-

mer position, and in so doing cut off the flow and close securely and neatly the opening in the nozzle. It will be seen that this construction affords a simple and exceedingly effective mechanism for dropping the contents of the batter pot, and that the operating parts are all located upon the exterior of the pot where they are readily accessible for cleaning and repairs.

10. A special advantage is gained by the loose connection between the cut-off valve and the bell-crank lever which actuates it.

By giving the valve a slight bend downward, as shown in dotted lines in Fig. 1 it will be disconnected from the end of the lever and made capable of endwise removal without the use of tools.

It is obvious that my invention might be varied in many slight ways that would naturally suggest themselves to a skilled mechanic. Therefore I consider myself entitled to all such variations as come within the spirit and scope of my invention.

Having thus described my invention, what 25 I claim as new, and desire to secure by Letters Patent, is—

1. In a batter dropper or similar device the combination of a funnel-shaped receptacle having a nozzle at the bottom, said nozzle being provided with a flattened end, a cut-off valve movable across said end and provided with a stop, and with an opening adapted to register with the opening in the nozzle, a spring-retracted thumb rod passing through

the handle of the receptacle, intervening lever mechanism connecting the thumb-rod and valve, and suitable guide lugs for the valve, substantially as described.

2. In a batter dropper or similar device, the combination of a funnel-shaped receptacle, a slide movable across the discharge orifice of the receptacle, said slide being provided with a recess registering with said orifice, a spring-retracted thumb-rod passing through the handle in connection with a lever located on the outside of the batter receptacle, and having its end passing loosely a short distance into the recess in such a manner as to allow the valve to be sprung clear of the lever, whereby the latter is removed, substantially as described.

3. In a batter dropper, the combination of a funnel-shaped receptacle, a cut-off valve at the smaller end of the receptacle, a bell-crank lever fulcrumed on the exterior of the receptacle, and connected to actuate the valve, and a thumb rod connected to the lever and having its upper end passing through the handle and located in such juxtaposition thereto as to be operated while grasping the handle, substantially as described.

In witness whereof I affix my signature in presence of two witnesses:

ESSEX L. LOMAX.
